(57) **CLAIM**

The ornamental design for closed compression-type coaxial cable connector, as shown and described.

DESCRIPTION

FIG. 1 is a perspective view of a closed compression-type coaxial cable connector showing my new design;

FIG. 2 is a side elevation view thereof, with the opposite side elevation view being a mirror image thereto;

FIG. 3 is a rear elevation view thereof;

FIG. 4 is a front elevation view thereof;

FIG. 5 is a top plan view thereof; and,

FIG. 6 is a bottom plan view thereof.

FIG. 1 is on a reduced scale and FIGS. 5 and 6 are on an enlarged scale.

The broken line showing of the environment is for illustrative purposes only and forms no part of the claimed design.
